(57) **CLAIM**

The ornamental design for an octopus shaped fish hook, as shown and described.

DESCRIPTION

FIG. 1 is a perspective view of an octopus shaped fish hook having a retention offset and the front length being at an angle to the shank.

FIG. 2 is a side view of a fish hook having a retention offset and the front length being positioned at a first angle to the shaft;

FIG. 3 is a rear view thereof;

FIG. 4 is a bottom view thereof;

FIG. 5 is a front view thereof;

FIG. 6 is a top view thereof;

FIG. 7 is a side view of a fish hook having a retention offset and the front length being positioned at a second angle to the shaft;

FIG. 8 is a rear view thereof;

FIG. 9 is a bottom view thereof;

FIG. 10 is a front view thereof; and,

FIG. 11 is a top view thereof.

The broken line showing of environment in the drawings is included for the purpose of illustrating only and forms no part of the claimed design.

1 Claim, 7 Drawing Sheets
